UNITED STATES PATENT OFFICE.

ARTHUR W. EICHMAN, OF DECATUR, ILLINOIS, ASSIGNOR TO ADOLPH MUELLER, ~~TRUSTEE~~, OF DECATUR, ILLINOIS.

DESIGN FOR A COMBINED SEAT AND TABLE.

Application filed December 16, 1921. Serial No. 522,932. Term of patent 14 years.

To all whom it may concern:

Be it known that I, ARTHUR W. EICHMAN, a citizen of the United States, residing at Decatur, in the county of Macon and State of Illinois, have invented a new, original, and ornamental Design for a Combined Seat and Table, of which the following is a specification, reference being had to the accompanying drawing, forming part thereof.

The figure is a perspective view of a combined seat and table unit showing my new design.

I claim:

The ornamental design for a combined seat and table, substantially as shown.

ARTHUR W. EICHMAN.
